UNITED STATES PATENT OFFICE

170,285

COMBINED DENTAL CUSPIDOR AND SHIELD

William B. Rice, Columbus, Ind.

Application February 26, 1952, Serial No. 18,670

Term of patent 14 years

(Cl. D24—1)

To all whom it may concern:

Be it known that I, William B. Rice, a citizen of the United States, residing at Columbus, State of Indiana, have invented a new, original, and ornamental Design for a Combined Dental Cuspidor and Shield, of which the following is a specification, reference being had to the accompanying drawing, forming a part hereof.

Figure 1 is a front view of a combined dental cuspidor and shield, showing my new design.

Figure 2 is a sectional view thereof taken along lines 2—2 of Figure 1; and

Figure 3 is a bottom view thereof.

I claim:

The ornamental design for a combined dental cuspidor and shield, as shown.

WILLIAM B. RICE.
